UNITED STATES PATENT OFFICE.

C. A. CUMMINGS AND C. DOUGLASS, OF NEW LONDON, CONNECTICUT.

GAS-BURNER.

Specification of Letters Patent No. 14,091, dated January 15, 1856.

To all whom it may concern:

Be it known that we, CHARLES A. CUMMINGS and CORTLAND DOUGLASS, of New London, in the county of New London and 5 State of Connecticut, have invented a new and useful Improvement in Gas-Burners; and we do hereby declare that the following is a full, clear, and exact description of the same, reference being had to the accompanying drawings, forming part of this 10 specification, in which—

Figures 1 and 2 exhibit central sections at right angles to each other on an enlarged scale of a "fish-tail" burner with our improvement applied. Fig. 3, is a top view of the same. Fig. 4, is a central section of a similar burner with the improvement applied in a different manner, and Fig. 5, a top view of the same.

20 Similar letters of reference indicate corresponding parts in the several figures.

This invention is applicable to what are known as fish tail burners or to other burners from which two jets of gas issue toward 25 each other. It consists in interposing a metal plate between the two orifices from which the gas issues, in such a manner that the two jets or streams of gas issuing therefrom will strike it on opposite sides and be spread into a broad sheet. This plate becomes highly heated and serves as a heat 30 reserver by which the gas is heated so as to produce a very perfect combustion and it spreads the gas into a broader sheet than 35 when the two jets or streams are spread by simply meeting each other and thereby gives a better light thus in two ways effecting a saving in the consumption of gas.

To enable others skilled in the art to 40 make and use our invention we will proceed to describe the manner of applying the same.

In the several figures *a*, *a*, are the orifices from which issue the two jets of gas, and *b*, is the interposed plate which constitutes 45 our improvement. This plate is made of any metal not easily oxidized or corroded, and may be of about one-fortieth of an inch in thickness but may vary considerably from this thickness. It is of a form approximating to an ellipse the major axis of which is in a horizontal direction. It fits close down to the top of the burner so that no gas passes under it. In Figs. 1, 2, and 3, it is represented as being secured to the burner by 50 being inserted tightly in two notches, *c*, *c*, cut diagonally across the edges of the burner so as not to interfere with the orifices *a*, *a*, and in Figs. 4 and 5, it is represented as being secured to an elastic split metal collar *d*, 55 which fits tightly over the top of the burner. Either of the above modes of applying the plate to the burner may be adopted with equal success but the last described mode possesses the advantage of enabling it to be 60 applied to any burner already in use without removing it. It is probable that other modes of applying the plate may also be employed and therefore we do not limit ourselves to those methods of applying it. In Fig. 3, 65 the plate is represented in dotted outline for the purpose of making the notches *c*, *c*, visible in bold outline.

What we claim as our invention and desire to secure by Letters Patent, is,

The interposition between two jets or streams of gas issuing from the same burner, of a plate *b*, substantially as and for the purposes herein set forth.

CHARLES A. CUMMINGS.
CORTLAND DOUGLASS.
